FIG. 1.

FIG. 2.

FIG. 3.

Arthur ZADEK

INVENTOR

BY *O. M. Zadek*

his ATTORNEY.

UNITED STATES PATENT OFFICE.

ARTHUR ZADEK, OF NEW YORK, N. Y.

TOY.

Application filed April 21, 1927. Serial No. 185,369.

This invention relates to nursery toys for very small children and particularly to the construction and equipment of a hollow head member for dolls, rattles and other articles 5 of this character.

The present invention is a further development of the moving eye rattle for which patent was obtained February 23, 1926, No. 1,574,341.

10 The object of my invention is to provide a hollow head member for dolls, rattles and articles of this character, having for its equipment the original moving eyes combined with a nursing bottle of transparent 15 material superimposed on the face of the head member, the bottle containing a quantity of milk-colored powder, sand or even fluid which may be made to flow into the interior of the head, at a point corresponding 20 to the mouth thereof, by tilting the toy backwards to discharge the bottle and forward again to refill it.

The invention is illustratively exemplified in the accompanying drawings, in which 25 Figure 1 is a front elevational view of my invention equipped with the moving eyes and nursing bottle partly filled with sand representing milk; Figure 2 is a substantially longitudinal sectional view of the 30 same, and Figure 3 is a perspective view of a toy doll carrying a nursing bottle which is arranged to discharge its contents into the child's mouth.

Referring to the drawing, 10 denotes a 35 holder to which a hollow head member 11 is attached, the latter comprising two sections shaped up of celluloid or similar material used in the manufacture of articles of this character. The front section 12 in the present 40 instance is molded and shaped to take on the features of a very young nursing baby's face, while the other section 13 merely corresponds to the back of the head. The front section 12 is provided with two flat 45 disc shaped places 13' representing the positions of the child's eyes, the places 13 being depressed and having inwardly directed center cavities 14 so as to locate and temporarily to hold a loose bead 15 therein. 50 Superimposed over these places 13 are hemispherically shaped transparent globes 16, the open end of each being permanently secured to the margins of the disc places 13. The eye chambers formed by this construction 55 permit the beads 15 to move around be-

neath the globes 16, thereby giving the features the appearance of moving eyes. The construction described so far is identical with that already set forth in the above mentioned patent.

60 A further development of my invention comprehends the construction of a nursing bottle comprising a transparent front section 17 superimposed on the front section 12 of the head 10. The neck portion of the bottle 65 17 is directed into the mouth of the child and is provided with a black coating of paint from a point well towards the body of the bottle to the lips to give the appearance 70 of the ordinary black nursing nipple 18. The portion of the front head section immediately beneath the front section of the bottle is depressed to form the other side 19 of the bottle. The side 19 follows the regular 75 shape of the bottle until it gets just beneath the blackened nipple portion 18 of the front bottle section 17 where it drops into the head to form a substantially deep pocket 20, the purpose of the positioning of the pocket being to render it invisible from 80 the face of the toy. Of course, the purpose of the hollow bottle is to enable the same to be filled or partially filled with white sand, powder or even liquid representing 85 milk, the filler 21 being preferably a dry easily movable sand which may be made to run up to the neck of the bottle and appear to enter the baby's mouth through the nipple 18, but in reality merely falls into the pocket 20 where it collects until the head is tilted 90 forwards sufficiently to cause the sand to spill out of the pocket to again collect in the body of the bottle.

95 In the modification illustratively exemplified in Figure 3, I have shown a doll 22 supporting with its hands 23 a nursing bottle 24 entirely of transparent material and adapted to discharge the contents thereof into the baby's mouth as if the child were actually nursing.

100 The operation of the device gives a striking likeness of a baby in the act of receiving nourishment from a nursing bottle containing an easily movable substance which will flow when the toy is simply tipped forwards or backwards.

105 In order that the other performance of the toy may be accompanied by a suitable noise making element I propose to enclose a few pebbles 25 within the hollow head, the peb-

bles causing a rattling noise when the head is tilted to move the eyes and discharge the contents of the bottle.

What I claim is:

The herein described head member for a toy, having in combination a pair of eyes comprising transparent eye chambers and loosely disposed pupils in said chambers, a nursing bottle superimposed on the front of the head member and having a nippled neck portion disposed in the mouth of the face of the head, said bottle comprising a transparent front section the neck end being

blackened to represent a nipple, the back portion of the bottle being a depressed portion of the front of the head terminating in a pocket disposed under the blackened portion of the transparent section, and an easily movable substance to represent milk disposed in the bottle and capable of moving 20 from the bottle to the pocket and from the latter back into the bottle when the toy is tilted.

In testimony whereof I affix my signature.

ARTHUR ZADEK.
